(57) **CLAIM**

(30) **Foreign Application Priority Data**

The ornamental design for an icon for a portion of a computer screen, as shown and described.

Aug. 7, 2000 (DE) 4 00 07 623
Aug. 7, 2000 (DE) 4 00 07 622

(51) LOC (7) Cl. **14-02**

DESCRIPTION

(52) U.S. Cl. **D14/489**

The single FIGURE is a front view of an icon for a computer screen showing the new design. The broken line drawing of a portion of a display screen is for illustrative purposes only and forms no part of the claimed design.
